CALKING TAPE

Alex Coutlee, Kankakee, Ill., assignor to J. W. Mortell Company, a corporation of Illinois

Application February 15, 1943, Serial No. 475,948

1 Claim. (Cl. 206—59)

This invention relates to calking material for use in weatherproofing buildings and the like, and more particularly to a convenient way of handling the material to facilitate its use.

The primary object of the invention is to provide calking material in the form of a tape which may be readily subdivided into strands of a convenient size for use such as in filling up the space between brick work and a window frame.

Another object of the invention is to put the insulating tape in a simple compact form that will facilitate shipping and handling and enable the user to take off conveniently the desired amount without waste.

Another object of the invention is to provide an improved method of manufacture whereby the strands of the material in the tape, due to the arrangement of mineral fibers in the strand, will have greater strength to resist longitudinal stresses than lateral stresses. Also, this arrangement of the fibers reduces the tendency of the strands to stick together in the tape and facilitate subsequent detachment.

The invention is illustrated in a preferred embodiment in the accompanying drawing, in which—

Figure 1 is a broken sectional view of the extruding device showing how the strands are formed, taken as indicated at line 1 of Figure 2; Figure 2, an end view of the extrusion head; and Figure 3, a perspective view of a spirally wound roll of the tape ready for use.

The calking material may be formed from suitable inert material, mineral fiber and an oil binder which preferably is non-drying or semi-drying. White or colored pigments may be used to give the desired color in the final product and aluminum silicate clays may be used as inert material to act as a filler and as an extender whereby the degree of adhesiveness of the compound may be regulated to a desired point. The final material should be soft enough to enable it to be worked with a putty knife but it should be sufficiently firm and tacky to enable it to be processed, spirally wound, and packaged without completely losing the form of strands provided by passage through the extrusion die.

A mineral fiber is used to give tensile strength to the extruded strand and preferably is strong and weatherproof. Asbestos fiber has been found to be very satisfactory.

The binder composed of oil or oils, vegetable or animal, is preferably of the non-drying or semi-drying type and may be bodied by heating or blowing in the usual manner, to give the desired consistency and binding properties necessary to hold the fillers, pigments, and fibers in proper relation and with the proper degree of stability.

The ingredients are mixed or kneaded into a dough-like mass in a mixer of the conventional type until the fibers are thoroughly dispersed

through the inerts and are wetted by the binder. This dough-like material 4 is then placed in an extrusion cylinder 5 where pressure may be applied to force it through an extrusion die 6 to form strands 7. The extrusion head is provided with a series of orifices 8 which communicate with tapered openings 8a leading to the inside of the cylinder. As shown diagrammatically in Figure 1, the fibers 9 are disposed at all angles when placed in the extrusion cylinder but the act of forcing them through the tapered openings causes the fibers to be disposed in a general longitudinal direction even though many of them are bent and folded into V-shapes. This arrangement of the fibers causes the strands to have more strength against longitudinal strains than lateral ones and facilitates handling without making the material too firm to be worked with a putty knife.

As the strands 7 leave the extrusion machine, they are brought into juxtaposition, as shown in Figure 3, so as to form a tape 10 which may be conveniently spirally wound on a suitable core 11 of cardboard or the like. The article of manufacture, illustrated in Figure 3, may be conveniently stored for long periods of time without drying out, and when it is desired to use the material, a length of the tape 10 may be unwound and one or more strands, as desired, may be pulled away from the tape to fill the desired opening. Long scraps of strands can be used so that there is practically no waste. The fact that the fibers in the strands are generally disposed longitudinally helps prevent the strands from becoming too firmly attached to each other or making it too difficult to unwind so much of the tape as is needed.

Although the material remains plastic, after being installed, it forms an effective permanent seal which does not become brittle in the winter or soften excessively in the summer. It may be washed without damage and may be painted, if desired.

The foregoing detailed description has been given for clearness of understanding only, and no unnecessary limitations should be understood therefrom for some modifications will be obvious to those skilled in the art.

I claim:

50 An article of manufacture comprising a spirally wound roll of plastic weatherstripping tape, said tape being formed of a plurality of parallel uniformly tacky strands of inelastic putty-like insulating material, said strands being detachably held in lateral juxtaposition by adhesion, and said tape being releasably held in spiral form by adhesion of each individual strand with outer windings of the same strand whereby an end strand may be entirely detached without unwinding the companion strands.
